Kansas

Application January 4, 1951, Serial No. 204,323

4 Claims. (Cl. 209—457)

1

The invention relates to the art of material separation by gravity action in a liquid medium such as performed on raw coal in washing the same and separating the coal from the refuse material intermingled therewith, and has more particular reference to a method and apparatus for discharging the hutch material from the hutch troughs of a coal wash box.

In the operation of a conventional wash box having operation on coal the separation of the coal takes place in a liquid medium disposed within one or more cells and the segregation of the refuse material is effected by the pulsating movement of the liquid, producing back and forth surging motion within each cell to alternately distend and then settle the material being treated while supported on screens or perforated plates. As the material progresses through the wash box the heavy refuse material and the middlings are separated therefrom and delivered to elevators which remove the waste material from the wash box. Hutch material comprising fine silica particles and the like is deposited in each cell. It has been customary to discharge this material from the hutch troughs by means of a screw conveyor. However, because the material is abrasive in character the screw conveyor is subjected to excessive wear and soon requires replacement.

An object of the invention is to provide a new and novel method and apparatus for removing material from the hutch troughs of coal washers and which makes use of the surging action of the water in the respective cells for propelling the material longitudinally of the troughs to the refuse elevators.

A more specific object resides in the provision of plate structure in the hutch trough centrally thereof for transforming the surging motion of the water into motion forwardly within the trough, first on one side and then on the opposite side thereof, for propelling the hutch material longitudinally of the trough to a point of discharge.

With these and various other objects in view, the invention may consist of certain novel features of construction and operation as will be more fully described and particularly pointed out in the specification, drawings and claims appended hereto.

In the drawings which illustrate an embodiment of the invention and wherein like reference characters are used to designate like parts—

Figure 1 is an elevational view, parts being shown in section, of a wash box equipped with

2

the new and improved structure of the invention for removing hutch material;

Figure 2 is a vertical longitudinal sectional view of the wash box of Figure 1 showing the wash chamber side thereof and also illustrating the improved hutch material removing structure;

Figure 3 is a detail sectional view of the primary section and adjacent elevator compartment of the wash box showing the hutch trough equipped with the plate structure of the invention;

Figure 4 is a plan view of the structure shown in Figure 3;

Figure 5 is a sectional view taken transversely through an elevator compartment and illustrating the elevator mechanism located therein;

Figure 6 is a sectional view taken along line 6—6 of Figure 4 and illustrating the T-formation of splitter plate and top plate; and

Figure 7 is a top plan view illustrating a modified form of the invention.

Referring to the drawings, which illustrate a preferred embodiment of the present invention, the wash box for cleaning material such as coal and the like by gravity separation in a liquid medium is indicated generally by numeral 10, Figure 1. The wash box is rectangular in plan elevation, consisting of side walls 11 and 12 and end walls 13 and 14. In elevation the end walls are approximately triangular and this is particularly so with respect to end wall 14 since this wall defines the end of one of the elevator compartments which characterizes wash boxes of this type. The side walls 11 and 12 join to form a semi-circular bottom wall 15 and it will be clearly seen from the drawings that this bottom wall is provided centrally of the wash box with hutch troughs, the hutch trough 16 being located at the entering end of the wash box and having association with the primary section, whereas, the trough 17 is located at the delivery end and has association with the secondary section. Supporting structure for the wash box is provided by the vertical standards 18 and 19, the same being located on the respective sides of the box and each transverse pair of vertical standards are supported by a foundation beam 20. The standards and beams are so placed as to permit location therebetween of the drainage boots 21 having location under the elevator compartments and into which the compartments are drained from time to time when it is desired to clean out the same.

The wash box is closed by a top wall 22 which extends for half the width of the box to form

55

the air chamber. The top may be open for the other half comprising the washing chamber. It is conventional with devices of this character for the air chamber side of the wash box to be equipped with air valves for admitting and exhausting air in order to effect the pulsations of the liquid within the box. It is also conventional that the washing chamber be equipped with material supporting screens or perforated plates. As shown in Figure 2, a perforated plate or screen 23 is located in the primary section, whereas a similar screen or plate 24 is located in the secondary section. The device shown in the drawings may be described as a two-section, six-cell type, the primary section at the entering end 15 consisting of two cells 25 and 26 formed by the transverse partition 27 and the secondary section consisting of four cells 28, 29, 30 and 31, formed by the transverse partitions 32, 33 and 34.

The coal to be treated, such as raw coal from the mine, is admitted to the washing chamber by the material receiving chute 35, located at the entrance end of the box and having a secured relation with wall 13. The treated or washed coal is discharged by the chute 36, extending from the end wall 14. In the primary section a centrally located, longitudinally extending baffle plate 37 functions to separate the air chamber half of the box from the washing chamber half, and a similar baffle 38 extends centrally and longitudinally of the secondary section. The air pulsations applied to the water in the air chamber of the wash box produces pulsations of the water transversely of the box with the result that the water surges back and forth on the order of thirty to sixty times per minute. The coal or other material supported by the screens 23 and 24 is continuously distending and settling in response to the pulsating water surges. The coal is cleaned in two stages in the present washer. Primary cleaning is effected in the cells 25 and 26 and the water surges, as regards these cells, may be extremely violent so as to stratify the heavy gravity material and the coal. The heavy refuse material is discharged through the discharge gate 40 into the refuse elevator compartment 41 which is defined by the transverse walls 42 and 43, Figure 2. Hutch material is also washed from the coal during primary treatment, the same passing through the screen 23 and collecting in the hutch trough 16. The invention provides new and novel means for propelling the hutch material longitudinally of the trough into the elevator compartment 41 and this structure will be presently described in detail.

The coal or other material from screen 23 will eventually pass over the weir 44 and supporting plate 45 to be discharged into the secondary compartment, consisting of cells 28 to 31 inclusive. The pulsations of the water are less violent as regards these cells and may be controlled to effect rather gentle back and forth surges of the water so as to stratify the coal supported by the screen 24 into relatively light gravity material generally referred to as middlings and clean coal. It may be desirable to effect the stratification of the material within the secondary compartment by pulsations or surges of the liquid of diminishing force from cell to cell. The middlings from the secondary compartment are discharged by gate 46, similar to gate 40, but which is located in the elevator compartment 41. Said elevator compartment is defined by wall 48 and the end wall 14 of the wash box. During treatment of the coal through the secondary compartment hutch

material will be washed from the coal and upon passing through screen 24 it will settle and be finally collected by the hutch trough 17. Here again the trough 17 is equipped with the improvement of the invention for propelling the hutch material forwardly along the trough for delivery into the elevator compartment 41.

Both compartments of the present box are provided with automatic refuse discharge mechanism, the same essentially consisting of a float 50 suspended by parallel link mechanism and balanced by an adjustable counterpoise generally indicated by numeral 51. The action of the float is free and unimpeded and as a result it is extremely sensitive to any change in the depth of the refuse bed which it automatically gauges. Action of the float in moving vertically as the depth of the refuse bed may vary is transmitted to air cylinder 52 operatively connected through linkage mechanism 53 to the gate 40. The gate is pivotally supported at 54 and in closed position the same is adapted to rest on the platform 55. When the refuse bed tends to build up the float rises to actuate the air cylinder 52, causing a wider opening of the gate 40. When the excess refuse is discharged the float will descend and again the air cylinder is actuated but in a reverse manner to reduce opening of gate 40 or possibly to even close the gate. Automatic refuse discharge mechanism is associated with both gates and gate 46 will likewise have opening and closing action to discharge the middlings and other refuse through the gate in response to the action of float 50 of its respective mechanism.

Each elevator compartment is equipped with elevator mechanism for removing the refuse material delivered to its respective compartment. The mechanism will be described in connection with compartment 41. Adjacent the bottom 58 of the same, as best shown in Figure 3, the compartment is equipped with a shaft 59 which is journaled at its respective ends by caps 60 and 61, the former cap being secured by screws 62 to wall 42. The space below the cap 60 is left open to facilitate travel of the hutch material along trough 16 and delivery of the same to said compartment 41. The cap 61 is secured to wall 43 at spaced points, top and bottom thereof, by screws 63 and 64, respectively. The shaft 59 journals sleeve 65 to which is secured at respective ends of the sleeve the sprockets 66. Said sprockets 66 are approximately square in side elevation, as best shown in Figure 5, being constructed in this manner for the purpose of engaging with the links 67 of the elevator chain having the buckets 68 secured thereto. Similar structure for supporting the elevator chain is provided at the top of the elevator compartment and the chain may be powered by an electric motor such as 70, Figure 1. Operation of the motor will produce movement of the endless chain to cause buckets 68 to travel in a clockwise direction, Figure 5, with respect to journaling shaft 59 so that the buckets will move downwardly adjacent wall 71 of the elevator compartment and upwardly as regards the opposite wall 72. As the buckets come in contact with the sprockets 66 they move around the lower extremity of the elevator compartment and dig into the refuse material and hutch material that has collected in the bottom of the compartment. The buckets remove the material and discharge the same exteriorly of the box. The above described structure of elevator mechanism for compartment 41 is repeated for elevator com-

partment 41. Whereas the elevator for compartment 41 will remove from the box the heavy refuse and hutch material deposited therein as a result of the primary separating operations, the elevator in compartment 41 will remove from the box the middlings and hutch material similarly deposited in this elevator compartment by the secondary separating operations. It may be desirable to periodically clean the bottom sections of the elevator compartments, for which purpose the drains 73 may be opened and the water and refuse discharging therefrom will be delivered to the drainage boots 21.

The present invention is concerned with the handling of the hutch material and delivery to the elevators of this fine material which is usually not larger than half an inch in size. In the past the hutch material has been handled by a screw type conveyor located in the bottom of the hutch troughs. Because of the abrasive characteristics of the hutch material such screw conveyors are subjected to excessive wear, and to replace a screw conveyor involves considerable time and expense. Also during replacement the plant is out of operation. The invention eliminates the screw conveyor and employs the positive force of the water surges for propelling the hutch material forwardly along the troughs. From the structural standpoint, the invention essentially resides in the provision of splitter plates in the troughs as best shown in Figures 1 and 6. With respect to trough 16, a splitter plate 75 is located centrally of the trough and extends longitudinally from end to end thereof, being greater in height than the depth of the trough.

The plate 75 is provided with a top plate 76 which, as shown in Figures 1, 2, 3 and 4, is imperforate. The two plates are joined on respective sides by the radius plates 77. Since trough 16 has a bottom which slopes downwardly in a forward direction, the splitter plate 75 progressively increases in height from wall 13 in a forward direction toward wall 42. However, the location of cap 60 within the trough at the forward end requires that the splitter plate terminate some distance rearwardly of wall 42 and at this point it will be seen that the top wall 76 is provided with an upturned flange 78. A removable top plate 79 is located in position over the cap 60, being secured at one end to flange 78 by the securing screws 80 and by screws 81 to wall 42 at its other end.

The trough 16, being on the longitudinal center of the wash box, is subjected to the action of the water surges in both directions. The splitter plate 75 transforms the surging motion of the water to motion forwardly within the trough first on one side and then the opposite side. The hutch material within the trough is thus propelled forwardly toward the elevator compartment 41. The hutch material is acted upon by the water in one direction only, or, in other words, there is no tendency for the water to wash the hutch material in a rearward direction along the trough. As the water surges toward one side of the wash box it has action on the hutch material deposited in the trough on that side of the splitter plate and as the water returns it has action on the hutch material deposited in the trough on the other side of the splitter plate. The action of the radius plate 77 is to direct the propelling force of the water downwardly toward the trough bottom. The water and the hutch material propelled thereby is discharged

from the trough into the elevator compartment 41. Naturally with the water being directed toward the elevator compartment, it might be expected that the water level in the compartment would rise to a point above the level within the wash box. It is relatively easy to provide a by-pass or opening in wall 42, for example, adjacent the upper end of the compartment for draining the water and returning the same to the washing chamber. However, it has been found that the present device works satisfactorily without such a by-pass.

The hutch trough 17 is also provided with a splitter plate 82 extending centrally of the trough and longitudinally from its rear end adjacent wall 43 to its forward end adjacent wall 48, and as a result the plate is located under the cells 28 to 31 inclusive. As described in connection with trough 16, a top plate 83 is provided and likewise the two plates are joined on the respective sides by the radius plates 84. The action of the water surges in the secondary compartment is the same as previously described and the hutch material is propelled along the sloping bottom wall of trough 17 in a forward direction to be discharged into the elevator compartment 41. The top plates 76 and 83 have been described as imperforate. In the modification shown in Figure 7 the top plate is provided with a plurality of openings and the plate has a stepped formation as will be described in detail.

Figure 7 shows a modified form of top plate 85 for the primary section of the washer. The plate is provided with a plurality of openings 86 and disposed centrally of the plate so as to extend longitudinally of trough 16 is the splitter plate 87. It will be observed that the section of the plate within cell 25 has a reduced width as compared to the plate within cell 26. This stepped formation can be carried out in a similar manner as the number of cells may increase. This modification is also characterized by baffles such as 88 which extend into the trough 16 on the respective sides of the plate, the baffles being located in alignment with partition 27. In other words, the baffles are located at intervals where the plate increases in width. In this modification the propelling force of the water surges is likewise used to discharge the hutch material from the trough. The action of the central splitter plate and top plate is to cause entrapment of the hutch material in the trough and which is then propelled longitudinally along the trough due to the pulsating surges of the water in the respective cells. The baffles 88 are provided for controlling flow within the trough of the water laden with hutch material and said baffles effectively prevent back wash such as might cause the hutch material to be recirculated in the cells.

The invention is not to be limited to or by details of construction of the particular embodiment thereof illustrated by the drawings as various other forms of the device will of course be apparent to those skilled in the art without departing from the spirit of the invention or the scope of the claims.

What is claimed is:

1. In a device of the character described, the combination with a tank, of a screen in the tank extending longitudinally and supporting coal or the like to be treated, means for periodically pulsating jiggling liquid within the tank to cause back and forth surging motion of the liquid

transversely of the tank, whereby the liquid will periodically pass through the screen to stratify the material thereon, a trough in the bottom of the tank below the screen and extending longitudinally in a direction parallel with the travel of the material through the tank, said trough having a bottom wall sloping in a downward direction from the entrance end of the tank to toward the delivery end thereof, a splitter plate located substantially centrally for the length of the trough and having a height greater than the depth of the trough, a perpendicular top plate supported by the splitter plate and extending horizontally for the length of the splitter plate, said top plate projecting on respective sides of the splitter plate for substantially the full width of the trough, and a radius plate of concave shape in cross-section disposed on respective sides of the splitter plate at the joint between the splitter plate and the top plate, said radius plates each directing the propelling force of the liquid downwardly toward the bottom of the trough, whereby said plate structure transforms the surging motion of the jiggling liquid into movement longitudinally within the trough to propel hutch material accumulated within the trough to a discharge point.

2. In a device of the character as defined by claim 1, wherein the top plate has a stepped formation increasing in width at intervals in a direction toward the point of discharge, and additionally including baffles on respective sides of the splitter plate at each stepped formation, said baffles each depending from the top plate and being laterally spaced from the splitter plate, and said baffles controlling the flow of liquid longitudinally within the trough to prevent backwash and recirculation of the liquid in the tank.

3. In a wash box of the character described, the combination with a tank, of a screen extending longitudinally of the tank for supporting coal or the like to be treated, means for periodically pulsating jiggling liquid within the tank to cause back and forth surging motion of the liquid transversely of the tank, whereby the liquid will periodically pass through the screen to stratify the material thereon, a trough in the bottom of the tank below the screen and extending longitudinally in a direction parallel with the screen, said trough increasing in depth in a direction from the entrance end of the tank.

toward the delivery end thereof, a splitter plate located substantially centrally for the length of the trough and having a height greater than the depth of the trough, a perpendicular top plate supported by the splitter plate and extending horizontally for the length of the splitter plate, said top plate projecting on respective sides of the splitter plate for substantially the full width of the trough, and a radius plate of concave shape in cross-section disposed on respective sides of the splitter plate at the joint between the splitter plate and the top plate, said radius plates each directing the propelling force of the liquid downwardly toward the bottom of the trough, whereby said plate structure transforms the surging motion of the jiggling liquid into movement longitudinally within the trough to propel hutch material accumulated within the trough to a discharge point.

4. In a jig, the combination with a tank, of a screen extending longitudinally of the tank for supporting coal or the like to be treated, a trough in the bottom of the tank below the screen and extending longitudinally in a direction parallel with the screen, said trough having a bottom wall sloping downwardly from the entrance end of the tank to the delivery end, a splitter plate having a height greater than the depth of the trough and disposed substantially centrally of the trough for the full length thereof, a perpendicular top plate supported by the splitter plate and projecting on respective sides thereof for substantially the full width of the trough, and a radius plate of concave shape in cross-section and disposed on each side of the splitter plate at the joint between the splitter plate and the top plate.
